UNITED STATES PATENT OFFICE.

HENRY D. RAHLING, OF BUFFALO, NEW YORK.

BIB MOUNTING.

Application filed November 22, 1924. Serial No. 751,489.

To all whom it may concern:

Be it known that I, HENRY D. RAHLING, a citizen of the United States, residing at Buffalo, in the county of Erie and State of New York, have invented a new and useful Improvement in Bib Mountings, of which the following is a specification.

In the shipment of oil in the drum or vessel from which it is dispensed it is essential that the said drum be completely sealed and therefore the bib or faucet which is employed to draw the oil from the drum is not fitted in the discharge opening but is arranged within the drum, and the cap which closes the filling opening is utilized for its support, the discharge opening being closed by a bung. When it is desired to dispense oil from the drum the cap which closes the filling opening is removed and the bib is detached therefrom after which the cap is replaced and the bung being removed the bib is fitted in the discharge opening so that it may be used to draw oil from the drum.

This invention relates to a transit mounting of the bib and its object is to provide simple and economical means for connecting it to the cap of the filling opening for support by such cap, as above explained, the said means by its co-operative combination with the cap and the bib securely holding the bib in place and affording facility in the connection and disconnection of the same relatively to the cap.

The invention is illustrated in the accompanying drawing, wherein:

Figure 1 is a partial sectional view of a drum showing the bib supported by the cap through the agency of a transit mounting of either of the forms herein disclosed or of any other form falling within the scope of the invention.

Figure 2 is a sectional view of the cap as fitted upon the drum and showing details of the mounting of the bib, the form shown in this figure being preferred as now considered.

Figure 3 is a bottom plan view of the cap and the means for the connection of the bib.

Figures 4 and 5 are a plan view and a side elevation of the means for the connection of the bib.

Figure 6 is a sectional view of the cap as

fitted upon the drum and showing details of an alternative form of bib mounting element.

Figure 7 is a bottom plan view partly in section of the cap and the alternative form of bib mounting element.

Figure 8 is an elevation of the alternative form of bib mounting element.

In Figure 1 D indicates the drum, B the bib, C the cap which closes the filling opening of the drum and from which the bib is supported and b the bung. As shown in Figure 2 the cap C has in its inner face a counter-sunk recess 1 of suitable depth in which the attachment end of the bib B is arranged, the end face of said bib abutting the base of the recess 1. The curved wall of the recess 1 is formed, at a suitable distance from the base of said recess, with an annular groove 2 which provides a seating for the element by which the bib is connected to and thereby supported from the cap C.

As shown in Figures 2 and 5 this connecting element is in the form of a split annular key 3 of suitable resilient metal or other material and of shallow frusto-conical outline. The outer circumferential edge of the key 3 engages in the groove 2 and the inner circumferential edge of said key engages in one of the convolutions of the usual threads provided on the attachment end of the bib. The bib is secured to the cap by engaging its threaded attachment end with the inner circumferential edge of the key 3 and threading the bib through the opening delimited by such edge which co-operates with the threads on the bib to cause the bib to move toward the base of the recess 1. This movement of the bib is continued until its end face abuts the base of the recess 1. The inner edge portion of the key 3 will obviously be distorted consequent to its conformation to the threads of the bib and thereby the free ends of the key 3 will at their relatively sharp inner corners engage the threaded shank of the bib with lock-washer effect, such engagement preventing accidental backward turning movement of the bib but offering no obstacle to the ordered turning movement of the bib when it is desired to disconnect the same from the cap C.

After the drum D is filled for shipment

the cap C with the key 3 sprung into position in the groove 2 thereof is connected to the bib B in the manner above described, after which the cap is screwed home in the 5 filling opening in the usual manner in order to close the drum, the bib being supported by the cap and projecting from the same into the drum, as shown in Figure 1. When it is desired to draw oil from the drum for 10 the usual purpose of retail sales the cap C is removed and the bib B disconnected from the same by unscrewing it from the key 3, after which the cap, with the key 3 in position therein and ready for re-use, is replaced 15 in the filling opening and screwed home. The bung b is then removed and the bib B substituted.

In the alternative construction shown in 20 Figures 6, 7 and 8 the key, in these figures designated as 3^a, is fashioned of resilient wire and includes two opposing curved outer portions 3^b which engage in the groove 2, two opposing curved inner portions 3^c which engage the convolution of the threaded 25 shank of the bib, a bow portion 3^d which connects the portions 3^c to one another and also engages in the groove 2 at a point between the ends of the portions 3^b, and two bow portions 3^e which connect the portions 3^c to the portions 3^b. The portions 3^c at 30 their ends adjacent the bow portions 3^e may, as shown, be slightly offset at opposite sides of the common plane of the portions 3^c to obtain a lock-washer effect in connection 35 with their engagement with the threads of the bib B.

Having fully described my invention, I claim:—

1. The combination with a cap for the 40 filling opening of a drum from which a liquid may be dispensed, of a bib mounting for connecting a bib to said cap and comprising a resilient element resiliently engaged with a surrounding wall of said cap and conformably and resiliently engageable

with the threads on the attachment shank of the bib.

2. The combination with a cap for the filling opening of a drum from which a liquid may be dispensed, said cap having a 45 countersunk recess provided in its annular wall with a circumferential groove, of a mounting key comprising a resilient element conformably engageable in said groove and conformably and resiliently engageable 50 with the threads on the attachment shank of the bib.

3. The combination with a cap for the filling opening of a drum from which a liquid may be dispensed, said cap having a 55 countersunk recess provided in its annular wall with a circumferential groove, of a mounting key comprising a split annular resilient element conformably engageable in said groove and conformably and resiliently 60 engageable with the threads on the attachment shank of the bib.

4. The combination with a cap for the filling opening of a drum from which a liquid may be dispensed, said cap having a 65 countersunk recess provided in its annular wall with a circumferential groove, of a split annular resilient key having its outer circumferential edge engaged in said groove and its inner circumferential edge conformably and resiliently engageable with the threads on the attachment shank of the bib.

5. The combination with a cap for the filling opening of a drum from which a liquid may be dispensed, said cap having a 70 countersunk recess provided in its annular wall with a circumferential groove, of a split annular resilient key of frusto-conical 75 form having its outer circumferential edge engaged in said groove and its inner circumferential edge conformably and resiliently 80 engageable with the threads on the attachment shank of the bib.

In testimony whereof I affix my signature.
HENRY D. RAHLING.
